Primary Examiner — Darlington Ly*Assistant Examiner* — Giang Hoang Tran(74) *Attorney, Agent, or Firm* — Philip C. Mendes da Costa; SMART & BIGGAR LP(57) **CLAIM**

The ornamental design for a bicycle frame as shown and described.

DESCRIPTION

FIG. 1 is a top, front and left side perspective view of a bicycle frame;

FIG. 2 is a front elevation view of the bicycle frame of FIG. 1;

FIG. 3 is a rear elevation view of the bicycle frame of FIG. 1;

FIG. 4 is a right side elevation view of the bicycle frame of FIG. 1;

FIG. 5 is a left side elevation view of the bicycle frame of FIG. 1;

FIG. 6 is a top plan view of the bicycle frame of FIG. 1; and, FIG. 7 is a bottom plan view of the bicycle frame of FIG. 1. The broken lines in FIGS. 1-7 illustrate portions of the bicycle frame that form no part of the claimed design.
